LANTERN BLACK-OUT DIMMER

Roy C. Miller, Beverly Hills, Calif.

Application June 5, 1942, Serial No. 445,832

4 Claims. (Cl. 240—11)

This invention relates to a lantern blackout dimmer.

The general object of my invention is to provide a novel means for enabling a lantern to be dimmed or extinguished for blackout purposes.

A more specific object of my invention is to provide a lantern including a pair of telescoping sleeve members so arranged that relative movement between the members will cause the light from the lantern to be dimmed or blacked out.

Another object of my invention is to provide a blackout dimmer including a pair of telescoping members together with novel means for operating the members.

A further object of my invention is to provide a novel blackout device for a lantern wherein a pair of relatively movable telescopic members are provided and wherein one of the members has slotted portions with louvers adjacent to the slotted portions.

Other objects and the advantages of my invention will be apparent from the following description taken in connection with the accompanying drawing wherein:

Fig. 1 is a front elevation, partly in section, showing a lantern embodying the features of my invention;

Fig. 2 is a rear elevation, partly in section, showing my invention;

Fig. 3 is a section taken on line 3—3 Fig. 1.

Fig. 4 is a fragmentary side elevation, partly in section showing a modification; and

Fig. 5 is a section taken on line 5—5 of Fig. 4 and showing the modification in blackout position.

Referring to the drawing by reference characters I have shown my invention as embodied in a lantern which is indicated generally at 10. The lantern may be of any general construction and preferably includes a base 11 having an upwardly projecting portion 12 which constitutes the burner. From the base 11 a yoke member 13 extends upwardly and is provided with a transverse top portion 14. From the top portion a stem 15 projects downwardly and supports a closure 16. The closure includes the customary depending resilient spring member 17. The parts of the lantern previously described are of the usual construction and form no part of the present invention.

The device constituting my invention includes an inner sleeve member 18 and an outer sleeve member 19 which is telescoped over the inner sleeve member. The inner sleeve member as shown is made of a pair of halves 20 and 21 (Fig. 3) which are united in seams 22. The seams 22 extend outwardly so that diametrically opposed external beads are provided.

The outer sleeve 19 is preferably made of a single piece of metal with the edges thereof joined at 23 to form a cylinder. The metal of the member 19 at opposed sides is indented inwardly as

at 24 to form an inwardly directed groove. The grooves 24 are diametrically opposed and are of a size to slidably receive the bead 22 on the inner member.

5 The inner member 18 is provided at its upper end with a flange 25 which includes a downwardly extending portion 26 and a lower outwardly extending peripheral portion 27. The portions 26 and 27 receive and engage a similarly shaped portion 28 on the upper end of a chimney 29. The lower portion of the chimney 29 is supported on a flange 30 on the lower portion of the lantern in the usual manner.

The spring member 17 engages the portions 15 26 and 27 on the flange 25 and thus holds the inner sleeve member 18 in place.

The outer sleeve member includes a plurality of outwardly punched louvers 31 which are downwardly directed and between the louvers 31 I 20 provide slots 32. The louvers 31, when the outer member 13 is lowered as shown in Fig. 2, direct light from the source 33 of the lantern outwardly and downwardly.

At the lower end, the inner member 18 includes an outwardly directed flange 34, while the upper end of the outer member 19 including an inwardly directed flange 35. When the outer member is lowered, as shown in Fig. 2, the flanges 34 and 35 engage and thereby limit the downward movement of the outer member.

The inner member includes a bottom closure 36 which has a central hole 37 which fits over the guard tip 38 of the burner when the outer member is lowered.

35 To hold the outer member in elevated position, the inner member is provided with a spring 36' fastened at 37' to the inner wall of the inner member. This spring 36' includes a shoulder 39 which passes through a slot 39' in the inner member and normally engages beneath the flange 35, as shown in Fig. 1. The spring 36' extends upwardly as at 40 from the shoulder 39 and then extends outwardly as at 41 between the flange 25 and the closure 16.

45 The construction is such that when the portion 41 is moved inwardly the shoulder 39 will be withdrawn from engagement with the flange 35 thereby allowing the member 19 to drop to dimming position.

50 To restore the outer member to non-dimming position the lantern may be inverted and the portion 41 moved inwardly whereupon a slight shake will cause the outer sleeve to move downwardly. If desired, a pull member 42 mounted on the outer member 18 at 43 and extending upwardly through a hole 44 in the closure 16 may be pulled to thereby lift the outer member.

55 My invention is particularly adapted for use with lanterns such as employed as safety lanterns by contractors and others as a warning

signal in connection with excavations, buildings, etc. In use the lantern is employed in the usual way and is left burning to give forth the warning light. In case an air raid alarm has been sounded, the air raid warden or other operator, to make the lantern dim, will press on the end 41 of the spring 36 and immediately the outer sleeve 19 will drop so that light from the flame 33 will be shielded by the outer sleeve. The light, however, will not be entirely extinguished since rays from the flame 33 may pass through the slots and impinge upon the louvers 31 whence they will be directed downwardly. The amount of light emitted will depend on the width of the slots 32 and the arrangement of the louvers 31.

After the blackout is over the outer sleeve may be returned to the position shown in Fig. 1 by pulling up on the member 42 or by pushing in on the end 41 of the spring 36 and inverting the lantern.

In Figs. 4 and 5, I show a modification of my invention wherein an inner tubular sleeve 50 is provided with vertical slots in its sidewall. This inner sleeve includes downward extending integral tongues 52 which are inserted through diametrically opposed holes 53 in the chimney supporting portion 30' of the lantern.

Mounted upon the inner shield I show a second sleeve 55 which is arranged exterior of the sleeve 51 and is provided with slots 56. The outer sleeve is rotatable on the inner sleeve and the slots in the two sleeves are preferably of uniform width and length so that in one position of the outer sleeve—as shown in Fig. 4—the slots are aligned so that light passes therethrough. When the outer sleeve is rotated on the inner sleeve the slots are moved out of alignment so that light from the light source is cut off. The outer sleeve includes a frusto-conical upper portion 56' and a reduced cylindrical portion 56''.

In order to rotate the outer sleeve this sleeve is provided with a finger 57 which is secured as at 58 to the outer sleeve. The finger 57 projects through a slot 58 cut in the portion 30'.

In use of the modification, the air warden engages the finger 57 and shifts the outer sleeve when the light is to be dimmed or blacked out and reverses the operation when the occasion for alarm is over.

From the foregoing description it will be apparent that I have invented a novel lantern blackout dimmer which can be economically manufactured and which is highly efficient for its intended purpose.

Having thus described my invention, I claim:

1. In a blackout lantern, a lantern having a chimney, an inner sleeve in said chimney, means on the lantern for holding the sleeve in place, an outer sleeve slidable on the inner sleeve, means to limit the movement of said outer sleeve on the inner sleeve, said outer sleeve having spaced slots therein, the portions of the outer sleeve above each of the slots being outwardly directed to form louvers, and a spring member secured to said inner sleeve, said spring member including a shoulder portion, said inner mentioned sleeve having a slot through which said shoulder portion projects, said shoulder being directed to engage the inwardly directed flange on the outer sleeve, said spring including an upwardly extending portion which terminates in the outwardly extending portion accessible from without the chimney.

2. In a blackout lantern, a lantern having a chimney, an inner sleeve in said chimney, means on the lantern for holding the sleeve in place, said inner sleeve having an outwardly directed flange on the lower end thereof, an outer sleeve slidable on the inner sleeve, said outer sleeve having an inwardly directed flange at its upper end adapted to engage the outwardly directed flange on the inner sleeve when the outer sleeve is slid along the inner sleeve, said outer sleeve having spaced slots therein, the portions of the outer sleeve above each of the slots being outwardly directed to form louvers, and a spring member secured to said inner sleeve, said spring member including a shoulder portion, said inner mentioned sleeve having a slot through which said shoulder portion projects, said shoulder being directed to engage the inwardly directed flange on the outer sleeve, said spring including an upwardly extending portion which terminates in an outwardly extending portion accessible from without the chimney.

3. In a blackout lantern, a lantern having a chimney, an inner sleeve arranged within said chimney, said inner sleeve having an outwardly directed flange at the upper end thereof, said flange engaging a portion of the chimney, means on the lantern for holding the flange in place, said inner sleeve having an outwardly directed flange on the lower end thereof, an outer sleeve slidable on the inner sleeve, said outer sleeve having an inwardly directed flange at its upper end adapted to engage the outwardly directed flange on the inner sleeve when the outer sleeve is slid along the inner sleeve, said outer sleeve having spaced slots, the portions of the outer sleeve above each of the slots being outwardly directed to form louvers, and a spring member arranged within said inner sleeve, said spring member including a shoulder portion, said inner sleeve having a slot through which said shoulder portion projects, said shoulder being directed to engage the inwardly directed flange on the outer sleeve, said spring including a portion accessible from without the chimney.

4. In a blackout lantern, a lantern having a chimney, an inner sleeve arranged within said chimney, said inner sleeve having an outwardly directed flange at the upper end thereof, said flange engaging a portion of the chimney, means on the lantern for holding the flange in place, said inner sleeve having an outwardly directed flange on the lower end thereof, an outer sleeve slidable on the inner sleeve, said outer sleeve having an inwardly directed flange at its upper end adapted to engage the outwardly directed flange on the inner sleeve when the outer sleeve is slid along the inner sleeve, said outer sleeve having circumferential slots therein arranged in spaced relation, the portions of the outer sleeve above each of the slots being outwardly directed to form louvers, a spring member arranged within said inner sleeve, said spring member including a shoulder portion, said inner sleeve having a slot through which said shoulder portion projects, said shoulder being directed to engage the inwardly directed flange on the outer sleeve, said spring including an upwardly extending portion which terminates in an outwardly extending portion accessible from without the chimney and a pull member mounted on said first mentioned sleeve.

ROY C. MILLER.
